UNITED STATES PATENT OFFICE.

GEORGE V. KNOFF, OF SANDUSKY, OHIO.

REED PROTECTOR.

1,410,066.

Specification of Letters Patent. Patented Mar. 21, 1922.

Application filed July 2, 1921. Serial No. 482,234.

To all whom it may concern:

Be it known that I, GEORGE V. KNOFF, a citizen of the United States, residing at Sandusky, in the county of Erie and State of

5 Ohio, have invented certain new and useful Improvements in Reed Protectors, of which the following is a specification, reference being had to the accompanying drawings.

This invention relates to attachments for 10 saxophones or clarinets, and particularly to attachments for protecting the reed of such instruments. These reeds are extremely delicate and when broken have to be replaced requiring time and patience to temper the 15 same and secure perfect tone quality. When a musician is not playing, these reeds, particularly on the saxophone, are constantly coming into contact with some portion of the body and are thereby liable to become 20 damaged, due largely to the fact that the tip of the reed is very fine and sensitive.

Reed protectors have been devised but in 25 most instances they require special attaching means for connecting them to the mouth-piece or they are entirely removable, similar to the removable mouth-piece cap now largely sold on the market. Those requiring special attaching means make their application expensive and most of them are 30 difficult to operate. The caps being entirely removable are constantly becoming lost or are left at some point where they are not available for instant application immediately after the musician ceases to play. 35 With the present protector, the cap is done away with entirely.

It is therefore the object of this invention to provide a simple and efficient attachment which will fully protect the reed 40 and which may be conveniently attached to the present reed ligature.

A further object is the provision of a 45 device of this character which may be attached to the present reed ligature and conveniently thrown into operative position or inoperative position.

Other objects of the invention will appear 50 as the following specific description is read in connection with the accompanying drawings which form a part of this application and in which:

Figure 1 is a side elevation of a clarinet or saxophone mouth-piece showing the protector in protecting position in full lines 55 and in inoperative or playing position in dotted lines;

Figure 2 is a top plan view showing the protector in the position to protect the reed, the reed being shown in dotted lines;

Figure 3 is a similar view with the protector thrown to inoperative position;

Figure 4 is a sectional view on the line 4-4 of Figure 1.

Referring more particularly to the drawing, 1 represents the mouth-piece of a saxophone or clarinet, and 2 the reed which is attached thereto by a ligature comprising a pair of bands 3 and 4 connected together at their lower sides by an integral strip 5. These bands are open, as is shown in Figure 70 2, and have their upper ends connected together by cross-bars 6. At the terminal ends of the bands there are provided the lugs 7 and 8, the latter of which is provided with a smooth bored aperture, and the former of 75 which is provided with a threaded opening 9 into which the clamping screws 10 are threaded. These screws, as shown in Figure 4, pass through the lugs 8 and are threaded into the lugs 7 and each provided with 80 thumb-pieces 11 by which the tension of the ligature on the reed may be adjusted.

The reed protector comprises a body 12 consisting of a flat strip of metal, the forward end of which is bent downwardly into 85 a protecting lip 13 adapted to overlie the tip end of the mouth-piece and the reed, as shown in Figure 1. The sides of the body overlap the sides of the reed a sufficient distance to prevent accidental engagement 90 of the reed at any point between its end and its connection with the ligature, as can be readily seen from an inspection of Figure 2.

Immediately forward of the band 4 of the ligature the body 12 is bent upwardly, as at 14, to provide a raised attaching end 15 extending rearwardly substantially parallel to the plane of the body and having its side edges adjacent the terminal thereof bent downwardly into attaching ears 16 apertured to receive the rear screw 10 of the ligature. These ears are arranged in parallel relation, as shown, and straddle the lug 8 on the rearmost band of the ligature one of said ears being clamped against the lug 8, as is shown in Figure 2, by the head of the screw 10.

As the protector body is pivotally mounted upon the screw it may be readily thrown to operative position, shown in full lines in 110 Figure 1, or to inoperative position shown in dotted lines of the same figure. The screw

may be utilized to increase the tension on the pivot ears so that the protector can not be accidentally displaced.

These protectors are of distinct advantage 5 as they can be thrown to operative position immediately after the musician ceases to play and as readily thrown to inoperative position when he is again ready to use the instrument. There is nothing to become lost 10 or displaced and the protector is attached directly to the ordinary ligature without any auxiliary parts.

What I claim is:

1. In a device of the class described, the 15 combination of a mouth-piece and a reed securing ligature having lugs, fastening means passing through said lugs for securing the ligature and the reed on the mouth-piece, and a reed protector having pivotal

ears straddling one of the lugs and apertured to receive the attaching screw, said protector being pivoted on the fastening means. 20

2. In a device of the character described, the combination of a mouth-piece and a separable reed securing ligature, the end portions of the ligature having lugs, said lugs having apertures for the reception of fastening means, and a reed protector having spaced ears provided on one end thereof, 25 30 said ears being adapted to straddle one of the lugs and apertured to receive the fastening means passing through said lug, one of said ears being clamped to said lug through the medium of said fastening means. 35

In testimony whereof I hereunto affix my signature.

GEORGE V. KNOPF.
